UNITED STATES PATENT OFFICE.

MARGARET T. HARTNACKE, OF GRAND RAPIDS, MICHIGAN.

PLAYING CARD.

Application filed August 17, 1928. Serial No. 300,330.

This invention relates to an educational-electrical game, the playing of which is based on fundamental principles of the use of electricity in the home.

5 The main objects of this invention are to provide a game which will educate and familiarize the persons playing it with the various steps necessary to secure electrical service in the home, various household appliances 10 commonly used for domestic purposes together with the amount of current consumed by each, and furthermore the most common kinds and sources of trouble experienced in the use of household electrical current together with the usual aids for overcoming 15 such troubles.

An illustrative embodiment of this invention is shown in the accompanying drawings, in which:—

20 Fig. 1 is a pictorial illustration of a playing card back, all of the cards being provided with this same design on their backs.

Fig. 2 is a plan view of a playing card having a pictorial illustration representing a 25 person making application to have electric service.

Fig. 3 is a plan view of the face side of a playing card having a pictorial illustration thereon representing another step in the securing of electric service.

30 Fig. 4 is a plan view of the face side of a playing card having a pictorial illustration thereon representing the final step in the securing of electric service.

35 Figs. 5, 6, 7, 8, 9 and 10 are plan views of the face sides of playing cards having pictorial illustrations thereon representing various domestic appliances for the use of electric current, together with numerals indicating 40 the number of watts used by the respective appliances.

45 Figs. 11, 12 and 13 are plan views of the face sides of cards having pictorial illustrations thereon representing the most common aids for overcoming troubles encountered in the use of domestic electric current.

50 Figs. 14, 15 and 16 are plan views of the face sides of playing cards having pictorial illustrations thereon representing the most common troubles encountered in the use of electric current.

55 In the illustrations shown in the drawings, the back of the card shown in Fig. 1 has a pictorial illustration 1 thereon representing a hydroelectric plant which is one of the common sources for generating electric current.

This view is shown in an outline which represents a round electric light bulb supported in a socket 2 which leads toward the center of the card, the upper right hand corner of the card has pictorial illustration 3 which represents a steam electric generating plant, which is the other common source of current generation. This view is likewise within an outline which represents a round electric light bulb supported in a socket which has wires leading toward the center of the card. The lower left hand corner of the card has a pictorial illustration 4 which represents a modern residence wherein electric current 70 would ordinarily be used.

The lower right hand corner of the card has pictorial illustration 5 which represents the interior of an electrically-equipped living room. Both of the last mentioned views are also within an outline which represents a round electric light bulb supported in sockets which have wires leading toward the center of the card. The center of the card has pictorial illustration 6 which represents an outdoor 80 electric line supported on cross bars mounted on the top end of the usual electric light pole. The words Live wire are written across the middle of the card and across the pictorial illustration 6, this name being preferably the 85 name of the card game.

Referring to Figs. 2, 3 and 4 which show the face views of a certain series of cards, known as "set cards", these cards have pictorial illustrations thereon which represent 90 the three usual steps in the securing of electric service in the home. The illustration 7 shows a woman making application over a counter to another woman, and the illustration 8 on the upper half of the same card 95 represents a woman making application over the counter to a man. The word Application appears twice on this card, once for each pictorial illustration. The arrangement of the pictorial illustrations and the wording therefor is optional, that is, some cards may be made so that the lower half is in readable position and others with the upper half in readable position, or all cards may be made with the matter in either of the positions 100 shown.

The face of the card shown in Fig. 3 has two pictorial illustrations 9 and 10 thereon, each occupying approximately one-half the face of the card and with the illustrations 110 facing in opposite directions. The pictorial illustration 9 represents an exterior view of

- a house showing electric wires run thereto, and underneath the word Service, showing that service has been wired into the house. The illustration 10 represents an electric 5 meter having the official red star 11 of inspection thereon, showing that the wiring has been inspected and is ready for use. Underneath this illustration appears the words Meter installation.
- 10 The face of the card shown in Fig. 4 has two pictorial illustrations 12 and 13 thereon, each occupying approximately one-half of the card and with the illustrations facing in opposite directions as is also the case with all 15 of the succeeding cards. The illustration 12 represents a silhouette view of a house with electric wires running to different outlets and shown in somewhat diagrammatic form. The illustration 13 is another view of an 20 electric meter having the seal of inspection thereon showing that the wiring has been completed and is ready for use. Four of each 25 of these "set cards" are provided in a pack.
- The face of the card shown in Fig. 5 has 30 pictorial illustrations 14 and 15 thereon, the illustration 14 showing a household appliance in the form of an electric fan 16. The upper left hand corner of the card has the 35 numeral 50 indicating that the fan uses fifty watts of current. The illustration 15 represents the interior of a bedroom and shows an electric heating pad 17, indicated by a red arrow 18. When this card is viewed with the 40 illustration in right-side-up position, the upper left hand corner also has the numeral 50 indicating that the heating pad consumes fifty watts of current.
- The face of the card shown in Fig. 6 has 45 pictorial illustrations 19 and 20 thereon, each showing two household appliances—in this case lighting fixtures which use one hundred watts each, the number 100 appearing in the upper left hand corner of each view when viewed in a right-side-up position. The illustration 19 shows a kitchen unit 21, which is 50 ordinarily equipped with one 100-watt lamp. The illustration 20 shows a utility fixture 22 which can be used either in the dining room or living room and which ordinarily takes four 25-watt lamps.
- The face of the card shown in Fig. 7 has 55 pictorial illustrations 23 and 24 thereon—in this case being an electric washing machine 25 and an electric vacuum cleaner 26 respectively, each of which devices ordinarily use one hundred and fifty watts of current, and the number 150 appears in the diagonally opposite corners in the same manner as on the preceding cards.
- 60 The face of the card shown in Fig. 8 has pictorial illustrations 27 and 28 thereon, arranged in the same manner as the preceding cards. The illustration 27 shows an electric exhaust fan 29, electric mixing motor 30 and 65 an electric dish washer 31 and the number

300 appears in the upper left hand corner indicating the current consumed thereby. The illustration 28 shows an electric refrigerator 32 and the number 300 which indicates the amount of current consumed in watts.

The face of the card shown in Fig. 9 has pictorial illustrations 33 and 34 on the two halves thereof in opposed relation. The illustration 33 shows an electric cooker 35 plugged into one side of a double service outlet 36 and the illustration 34 shows an electric iron 37. The number 500 appears in the respective upper left hand corners of each of these illustrations to show the number of watts consumed by each.

The face of the card shown in Fig. 10 has pictorial illustrations 38 and 39 in opposed relation thereon. The illustration 38 is of an electric water heater and the upper left hand corner is marked 1 K W., meaning one kilowatt of current. Illustration 39 shows a fragmentary view of an electric range 40 and a red arrow 41 indicates one heating plate of the range which uses one kilowatt of current as indicated by the 1 K W. placed in the corner of the card. Four of each of these appliances or device cards are provided in a pack.

These cards having the number of watts in the corners thereof constitute the building-up set of cards which may be played on the "set cards" shown in Figs. 2, 3 and 4 until the total number of points reach the required total to win a game, as will be hereinafter more fully explained.

The face of the card shown in Fig. 14 has pictorial illustrations 42 and 43 thereon. The illustration 42 shows a vacuum cleaner 44 connected to a service outlet by a cord which has become frayed and worn at the point 45 and caused a short circuit by blowing out a distribution fuse. The words Short circuit appear in red underneath the illustration. Illustration 43 shows a short circuit caused by the cord of a washing machine 46 getting in a puddle of water 47 and thereby becoming shorted at the point 48 as indicated by the red arrow 49, and the words Short circuit also appear in red when viewed in the right-side-up position. Three of these cards are provided in a pack.

The face of the card shown in Fig. 11 has pictorial illustrations 50 and 51 thereon which show a 15 ampere distribution fuse 52 and a fuse box 53 for housing the distribution fuses 54. These fuses are the ones which ordinarily are blown out by the short circuiting of household appliances. The words Fuse 15 amp. appear above each of these illustrations and the words Distribution fuse appear below each of these views respectively when viewed in their right-side-up position. Three of these cards are provided in a pack.

The face of the card shown in Fig. 15 has

illustrations 55 and 56 thereon, each occupying one-half of the card and being placed in opposed relation to each other in the same manner as the other cards of the deck. Illustration 55 shows a common kind of trouble occasioned by the use of two and three way sockets attached to a lighting fixture and two appliances—in this case a toaster 57 and a percolator 58—both attached at the same time and which very often overloads the circuit thereby blowing out a main fuse. The illustration 56 also has a base-board service outlet with several two-way plugs, all of which run to various lights not shown, this being another common way of overloading a circuit. The word Overload appears underneath each of these views. Three of these cards are provided in a pack.

When a circuit is overloaded, very often the main fuse is blown out and this is shown in the illustrations 59 and 60 shown on card illustrated in Fig. 12. A main fuse 61 is shown with the words Main fuse thereabove and the words 30 Ampere fuse underneath. Illustration 60 shows a main fuse box 62 for housing the main fuses and the words Main fuse appear above the illustration and the words 30 Ampere fuse appear below it. Three of these cards are provided in a pack.

30 A third kind of trouble is experienced by domestic users of electric current and this is known as an appliance breakdown, as shown by the illustrations 63 and 64 in Fig. 16. Illustration 63 shows a washing machine 65 with a repair man working on the motor thereof and the words Appliance breakdown appear in red below the illustration. The illustration 64 shows one end of an electric ironer 66 with a repair man working on the electric motor thereof and the words Appliance breakdown appear in red underneath this illustration. Two of these cards are provided in a pack.

When a user experiences an appliance breakdown, it is ordinarily necessary to secure the services of a repair man and the manner in which this is done is shown in the illustration 67 of Fig. 13 which shows a woman telephoning for repair service. The words Repair service appear underneath the illustration. The other half of the card shown in Fig. 13 has an illustration 68 thereon which shows a repair man calling at the house of the consumer for the purpose of taking care of the appliance breakdowns. Two of these cards are provided in a pack.

60 The pack of cards preferably consists of fifty-two of the illustrated cards apportioned as heretofore mentioned and can be played by two, three or four persons. To play the game, the cards are thoroughly shuffled and seven cards are dealt to each player, the balance of the cards being placed in the center of the table, face down, and the top card is turned over as a choice for the first player.

The party at the left of the dealer then begins playing. The three "set cards", shown in Figs. 2, 3 and 4, must first be secured and played down on the table, face up, in the order named by each player before the player 70 begins to build up the load-building cards illustrated in Figs. 5 to 10 inclusive.

After the player has the three set cards played in the order of rotation, he can begin playing the load-building cards which have 75 the values of 50, 100, 150, 300, 500 and 1000, this latter card having the indicia 1 K W., meaning 1000 watts which equal one kilowatt. A player can also play interference cards on other players after they have begun building with their load cards. These interference cards being the ones represented in Figs. 14 to 16 inclusive. Only one interference or "stop" card can be played on any one of the opponent's cards at one time. For instance: 80 If after he has built up his electrical service to 500 watts, an opponent should play on his cards the overload card shown in Fig. 15, he in turn would have to get the Main fuse 30 ampere card, illustrated in Fig. 12, to put 85 on the top of his playing pile before he could go on building up with the load cards. After he has obtained the same, then if another player wishes to stop his further playing, another card such as Short circuit or 90 Appliance breakdown may be placed on his stack thereby requiring him to get the appropriate clearance card before continuing with his play.

The object of each player of the game is to 95 build the consumption to "3 K W." (3000 watts—which is game) as readily as possible—consequently the highest energy cards held in hand should be played first. The idea of the "stop cards" of Short circuit, Overload and Appliance breakdown is that these will serve as interference for opponent working towards "game" and he cannot play energy cards (50—100—150—300—500—1000 watt) until he has "clearance card" to correspond to "stop card", namely Distribution-15 ampere fuse, Main fuse-30 ampere, Repair service, respectively. The total wattage of electrical consumption is kept during the entire game, i. e., until at least "3 K W." is attained, in spite of the "interference cards" 100 that may be played on anyone's set-up of cards from time to time.

The object of each player is to build up his 110 electrical consumption to "3 K W." as soon as possible after the three "set cards" are obtained—thereby attaining game—in the meantime stopping other parties playing as often as possible necessitating their getting 115 "corresponding card" before they can go on playing.

120 Each player must either draw from discard pile or pile turned face downward each time. They may also play on any one of the opponents' piles any of the "interference cards".

They may also play on their own cards before them—but only one card on his own layout each time around. Everyone must discard each time if he has at least one in his hand and continue to draw and discard each time.

After the deck in center of table has been used up, same may be reshuffled, then turned face downward and used again and again until someone gets the game. The "Live wire" can continue progressively for six or eight games, the various parties score going in the hole for the amount he lacks toward the goal of game "3 K W." If party attaining "game" is in excess of 3 K W. and the game is being played progressively, the surplus score is kept and the one having the highest surplus wattage at final game being winner.

Although certain views, appliances and illustrations have been shown and described for the playing of this game, it will be understood that various other appliances and views may be used for the purpose of securing the educational value herein described without departing from the spirit of this invention as defined by the following claims.

I claim:

1. A pack of playing cards having upon their faces pictorial illustrations representing various phases in the procedure of securing service of electric current, other cards having upon their faces pictorial illustrations showing household appliances and devices used by consumers of current, other cards having upon their faces pictorial illustrations representing sources of trouble encountered in the use of such current, and other

cards having upon their faces pictorial illustrations representing aids for overcoming such troubles.

2. A pack of playing cards having upon their faces pictorial illustrations representing various phases in the procedure of securing service of electric current, other cards having upon their faces pictorial illustrations showing household appliances and devices used by consumers of current with designations of the wattage consumed by said devices respectively, other cards having upon their faces pictorial illustrations representing sources of trouble encountered in the use of such current, and other cards having upon their faces pictorial illustrations representing aids for overcoming such troubles.

3. A pack of playing cards having upon their faces pictorial illustrations representing various phases in the procedure of securing service of electric current, other playing cards having upon their faces pictorial illustrations showing household appliances and devices used by consumers of current together with designations of the wattage consumed by said devices respectively, other cards having upon their faces pictorial illustrations representing sources of trouble encountered in the use of such current, and other cards having upon their faces pictorial illustrations representing aids for overcoming such troubles.

In testimony whereof I have hereunto set my hand at Grand Rapids, Michigan, this 8th day of August, 1928.

MARGARET T. HARTNACKE.
